INVENTOR
WILLIAM REES.

BY Harrya Beine
ATTORNEY.

UNITED STATES PATENT OFFICE

WILLIAM REES, OF ST. LOUIS, MISSOURI

DEVICE FOR TREATING ARTICLES OF FURNITURE

Application filed August 30, 1930. Serial No. 478,994.

My invention has relation to improvements in devices for treating articles of furniture and it consists in the novel features of construction more fully set forth in the specification and pointed out in the claim.

More specifically the device comprises a spray gun and a spray nozzle associated therewith, the former embodying features for cooperation with the nozzle to produce an efficient and simple device for penetrating mattresses or other padded articles and injecting a suitable liquid in a highly atomized condition thereto for the purpose of destroying bacteria, preventing the nesting therein of insects.

Further object of the invention is to provide a spray nozzle in the shape of a needle that may be inserted into the padding of an article without injury thereto and that is provided with a mixing chamber for air and the liquid insecticide so that the latter discharges from the outlet apertures in a highly atomized condition and the insecticide will be caused to thoroughly impregnate the padding without noticeably saturating the same. Further and other advantages will be better apparent from a detailed description of the invention in connection with the accompanying drawings, in which—

Fig. 1 is a side elevation of my improved device with parts shown in section; Fig. 2 is an enlarged longitudinal section through the spray needle; and Fig. 3 is a further enlarged section through the spray needle with a part thereof broken away.

Referring to the drawings showing a preferred embodiment of the invention, 1 represents a suitable container for the insecticide having a screw top 2 into the upper reduced portion 3 of which is screwed a stem 4 of a hand pump 5. A tubular housing 6 is screwed into the cap portion 3 opposite the pump stem 4 and a liquid ejector tube 7 traverses the tubular housing 6 and is bent so as to extend downwardly into the container 1. The outer end of the tubular housing 6 is threaded to receive a coupling member 8 fixed on the inner end of a hollow needle or spray nozzle 9. The needle 9 fits tightly in a socket 10 of the extended portion 11 of

coupling 8 and in the wall 12, between socket 10 and threaded socket 8', is an opening 13 somewhat smaller in diameter than the bore 14 of the hollow needle. When the needle is in place on the tube housing 6 the wall 12 will bear against tube 7 with the hole 13 in alignment with the tube 7 which has its adjacent edge serrated, as shown at 7', to permit air to pass from the housing 6 into the bore 14 of the needle. 55

It will be observed that the point 15 of the needle is a separate element shouldered at 16 and securely fixed into the outer end of the spray nozzle 9. The reason for this is that the point must be of sufficient temper 60 and strength to withstand repeated puncturing of the material that is to be treated.

Still another advantage is obtained by having the point 15 as a solid member, that is, the inner end 17 of the point furnishes an 70 abutment wall against which the mixture of air and liquid impinges to assist in the operation of breaking up particles of liquid into a finely atomized condition. The mixture of air and fluid that enters the chamber 75 14 of the spray nozzle discharges therefrom through three radially disposed openings 18 spaced a short distance from the inner end 17 of point 15. I have found that the sum of the areas of the openings 18 should be approximately equal to the area of the port 13 so as to restrict the amount of air ejected through these openings with the liquid insecticide. I wish to avoid any degree of vaporization of the insecticide as I have 80 found that the best results are obtained by injecting the insecticide in a finely atomized condition. In other words, the liquid particles of insecticide are more effective in destroying pests than vaporized insecticide. 85 The advantage of the wall 17 immediately beyond the openings 18 is that the impingement of the liquid insecticide against this wall just before the insecticide discharges from the openings 18 will operate to break 90 the column of liquid into very small globules and insure its leaving the said openings in a highly atomized condition.

I have found in practice a spray nozzle constructed as just described is very effective in 100

treating upholstered furniture, cushions, etc. to prevent their becoming infested with moths, tow bugs, or other vermin. Then, too, the spray is in such a highly divided condition that there is no danger of staining the surface of the articles by an excessive discharge of liquid.

Having described my invention, I claim:

- In combination with a liquid ejector tube,
10 a spray nozzle comprising a coupling member and a nozzle tube of substantially uniform bore fixed to said coupling member, said coupling member having a socket into which the ejector tube is received and a constricted
15 passageway between the nozzle tube and socket, and a solid point element fixed at the end of the nozzle tube opposite to the coupling element, said nozzle tube having radial apertures adjacent to the point element, and
20 said ejector tube having a serrated edge enveloping the constricted passageway.

In testimony whereof I hereunto affix my signature.

WILLIAM REES.
